The ornamental design for a phaco-emulsifier tip for ophthalmic surgery, as shown and described.

DESCRIPTION

FIG. 1 is a perspective view of the phaco-emulsifier tip of the present invention;

FIG. 2 is a top plan view thereof;

FIG. 3 is an end elevational view thereof;

FIG. 4 is a side elevational view thereof;

FIG. 5 is an end elevational view thereof opposite that shown in FIG. 3; and,

FIG. 6 is a bottom plan view thereof.

FIG. 1

FIG. 2

FIG. 3

FIG. 5

FIG. 4

FIG. 6
